UNITED STATES PATENT OFFICE.

FRANK JACKSON, OF DENVER, COLORADO.

AIR-INLET VALVE FOR INTAKE-MANIFOLDS OF INTERNAL-COMBUSTION ENGINES.

Specification of Letters Patent. Patented Aug. 24, 1915.

1,151,105.

Application filed May 14, 1914. Serial No. 838,569.

To all whom it may concern:

Be it known that I, FRANK JACKSON, a citizen of the United States of America, residing in the city and county of Denver 5 and State of Colorado, have invented a new and useful Air-Inlet Valve for Intake-Manifolds of Internal-Combustion Engines, of which the following is a specification.

My invention relates to improvements in 10 valves for admitting air to the intake manifolds of internal combustion engines, and more particularly the style of engine used in connection with automobiles.

The object of the invention is to provide 15 a valve of this character which can be operated by the person at the steering wheel to admit additional air to the gas mixture in this intake manifold in varying quantities, as may be required, whereby increased 20 power and efficiency of the engine is obtained with a smaller consumption of fuel, and a consequent minimizing of the heating of the engine. I accomplish these objects by the mechanism illustrated in the accompanying drawings, in which:

Figure 1, is a side view illustrating the application of the valve to an automobile engine, and the manner of its operation from the steering wheel. Fig. 2, is a front view 30 of the valve, the inlet thereof being partially uncovered. Fig. 3, is a view the reverse of Fig. 2. Fig. 4, is a sectional view on the line 4—4 of Fig. 2. Fig. 5, is a front view of the operating lever and parts by which 35 it is secured to the steering post. And Fig. 6, is a side view of Fig. 5.

Similar letters of reference refer to similar parts throughout the several views.

Referring to the accompanying drawings,—the numeral 1 indicates the cylinders 40 comprising the engine of an automobile; 2, the carburetor; and 3, the intake manifold, which connects with the engine in the usual manner. The intake 3 at a suitable point 45 above the carburetor, is provided with a threaded aperture, in which is screwed one end of a stem 4, having an axial inlet hole 5. This stem constitutes the main or body 50 portion of the valve, and is preferably hexagonal in cross section in order to accommodate a wrench. The outer end of the stem terminates in a short reduced portion or neck 6, upon which is mounted a plate 7, which is rigidly held thereon, by upset-

ting the end of the neck upon the plate, as 55 shown in Fig. 4, the upset portion 8 extending slightly above the plate, and its surface being smoothly finished to form a valve seat. The plate 7 is preferably of the form shown in Figs. 2 and 3, and is provided 60 with extensions 9 and 10. The extension 9 has an offset 11 at its extremity, which is on a level with the valve seat 8, and resting upon the offset 11, and the valve seat 8 is a cap or plate, which forms the cut-off 12 of 65 the valve. This cut-off is pivotally secured to the extension 9, adjacent to the offset 11, by a screw 13, between the head of which and the cut-off 12 is interposed a bowed spring washer 14, which exerts a continuous 70 resilient tension upon the cut-off, whereby the same is held in close contact with the valve seat, and the wear, both of the seat and cut-off, is automatically compensated. The portion of the edge of the cut-off which 75 passes over the inlet 5, is preferably formed into a semi-circular recess of a radius corresponding to that of the said inlet, and as the cut-off is turned upon its pivot screw 13, the mouth of the inlet may be contracted to 80 admit varying quantities of air, or the inlet may be wholly closed or wholly opened, as conditions may require. The free end of the cut-off extends beyond the adjacent edge of the plate 7, and is provided with an ap- 85erture in which one end of a flexible, operating wire 15 is secured, the opposite end of which is connected to an operating lever, to be hereinafter described.

The extension 10 of the plate 7, termi- 90 nates in a strip 16, which extends at right angles to the extension, and this strip is folded or bent upon itself, to form an eye or loop 17, in which is held one end of a flexible tube or housing 18, by clamping the 95 free end of the strip 16 to the extension 10, by a screw 19, as shown in Fig. 2. The housing 18, is preferably in the form of a tightly-wound coil of flexible wire, the axial pas- 100 sage through which is of sufficient diameter to allow the operating wire 15 to pass loosely through it. The opposite end of the housing is connected to the steering post 20, adjacent to the steering wheel 21, in the following manner: Upon the steering post, 105 adjacent to the steering wheel, is rigidly secured a supporting plate 22, by a yoke 23, which surrounds the steering post, the ends

of which are threaded and pass through apertures in the ends of the plate 22, and receive clamping nuts 24. The plate 22 is outwardly bowed, as shown, and upon the bowed portion is riveted, or otherwise rigidly secured, a plate 25, the free end of which terminates in a strip, which is folded or bent upon itself to form an eye or loop 26, which holds the other end of the flexible housing 18, the extremity of the said strip being screwed down upon the plate 25, so as to clamp the end of the housing 18 within the eye 26. The other end of the wire 15, which extends out through the latter end of the housing 18, is secured to an operating lever 27, one end of which is pivotally connected to the plate 25. By operating the lever 27, the wire 15 is caused to turn the cut-off 12, to the limit of its opening or closing movement, or to any intermediate point, thereby to admit air in any required quantity to the intake manifold, in excess of that which passes through the carbureter. The lever 27 is clamped by its pivot against the plate 25, to produce a frictional contact between the said lever and plate, and by this means, together with the pressure exerted by the bowed spring washer 14, the cut-off 12 is securely held at any point of adjustment.

The flexible housing can be curved to conform to any necessary outline, in extending it from the intake manifold to the operating lever on the steering post, and the wire 15 being flexible, is not affected thereby, and as the housing prevents the wire 15 from buckling, any thrust or pull at one end by the operating lever transmits a corresponding action at the other or cut-off operating end of the wire.

Having described my invention, what I

claim as new and desire to secure by Letters Patent, is:

1. The combination with the intake manifold of an internal combustion engine, of an inlet valve, comprising a tubular stem, having a threaded end which is screwed into said manifold, a plate secured upon the opposite end of said stem, said end extending slightly beyond said plate to form a valve seat, an offset on said plate on a level with the valve seat, a screw extending through said plate adjacent to said offset, a cut-off pivotally mounted on the screw and bearing on the said valve seat and offset, and a bowed resilient washer interposed between the cut-off and the head of the screw.

2. The combination with the intake manifold of an automobile engine, of an inlet tube threaded to said manifold, having a short neck at its outer end, a plate having an aperture which fits upon said neck, said neck being upset upon said plate to hold the same upon the tube, the upset portion also forming a valve seat which is slightly raised above the surface of the plate, an offset on said plate, on a level with the valve seat, a cut-off which rests upon said valve seat and said offset, a screw for pivotally connecting said cut-off to said plate, which enters said plate between the offset and valve seat, and a resilient bowed washer interposed between the head of the screw and the cut-off, and means for operating the cut-off.

In testimony whereof I affix my signature in presence of two witnesses.

FRANK JACKSON.
